STRAIGHT KNITTING MACHINE

Application filed August 1, 1930. Serial No. 473,819.

This invention relates to improvements in straight knitting machines and particularly to that class thereof which are known as full fashioned machines for the production of knit fabric in the manufacture of hosiery.

Machines of this class are provided with a number of aligned rows of needles which are simultaneously operated in conjunction with sinkers, dividers, knock over bits, thread feeding devices and fabric take-up devices for the production of a plurality of like stocking blanks or parts of knit fabric; and, in the knitting of such blanks or parts, prior to my invention, much difficulty has been experienced in preventing what is known as sleazy knitting which is the production of knit fabric whose loops are misshapen and of irregular and ununiform character.

An object of my invention is to overcome the aforesaid difficulty and I accomplish my object by the provision of a means for causing a novel cooperation of the needles and the sinkers and dividers and the fabric being produced by the machine whereby the thread loops of each succeeding fresh row thereof which are added to the finished portion of the fabric are maintained in even and uniform condition while being added to the fabric.

Another object of the invention is to dispense with the function of the knock over bits of supporting or moving the fabric being produced, while the needles operate to draw the succeeding rows of freshly formed thread loops through the previously formed rows of loops.

Another object of the invention is to provide a knitting machine of novel construction which will produce knit fabric having even and uniform thread loops under greatly varying conditions in the various characteristics of the thread, and particularly silk thread, which is formed into the fabric loops.

The invention consists in the novel construction, combination and arrangement of parts hereinafter described and claimed.

In the accompanying drawings, illustrating the invention,

Figure 1 is a transverse section through a knitting machine constructed in accordance with my invention.

Figure 2 is a similar view, omitting a number of the parts shown in Fig. 1.

Figure 3 is a view of some of the parts shown in Figure 2, showing another position thereof.

Figure 4 is a front view of some of the parts of the machine shown in Fig. 1.

Figure 5 is a detail in plan, showing part of the mechanism for raising and lowering the fabric being produced by the machine.

Figure 6 is a side view of one of the sinkers.

Figure 7 is a side view of one of the dividers.

Figure 8 is a front view of several of the needles, several of the sinkers and dividers, and several of the knock over bits.

Figures 9, 10 and 11 are greatly enlarged sectional views showing progressively advanced relative positions of the fabric, the needles and the forward end portions of the noses of the sinkers and dividers during the knitting operation.

Figure 12 is a top view of the parts shown in Fig. 10.

Referring to the drawings, 2 designates the frame of the machine, 3 the needles, 4 the thread carrier, 5 the sinkers, 6 the dividers and 7 the fabric supporting the knock-over bits.

In the type of knitting machine herein illustrated, the needles 3 are arranged in a number of spaced and aligned rows, two such rows, designated A and B, being shown in Fig. 4, and the needles are simultaneously actuated during the knitting operation for the production of a stocking blank or part by each row thereof.

The needles 3 of each row thereof are secured to and carried by a horizontally extending bar 8. The needle bar 8 is provided with downwardly extending brackets 9 which are pivoted, at 10, to arms 11 which are fixed to and extend rearwardly from a rockable shaft 12. This shaft 12 is mounted to turn in suitable bearings on the machine frame and it is provided with a downwardly extending arm 13 carrying a roller 14 which bears against a cam 15 on the cam shaft 16 which turns in bearings on the machine 100.

frame and which is rotated in the usual manner during the operation of the machine. The roller 14 is held in contact with the cam 15 by a spring 17 which is connected to the lower end of the arm 13 and to a bracket 18 on the machine frame 2. The cam 15 acts upon the roller 14 and its arm 13 to rock the shaft 12 and move the arms 11 up and down for raising and lowering the needle bar 8 and the needles 3 carried thereby.

The needle bar 8 and therewith the needles 3 are moved forwardly and rearwardly on the axis of the pivotal connections of the brackets 9 with the arms 11; and, for this purpose the bar 8 is provided with a downwardly extending arm 19 whose lower end is pivoted to a forwardly extending arm 20 which is pivoted to an arm 21 by means of a pin 22 which extends into a pocket 23 formed in the arm 20. The arm 21 extends downwardly from and is fixed on a rockable shaft 24 which turns in bearings on the frame of the machine. The lower end portion of the arm 21 carries a roller 25 which bears against a cam 26 on the cam shaft 16. The roller 25 is maintained in contact with the cam 26 by a spring 27 which extends between and is connected to the arm 21 and the frame bracket 18. The cam 26 acts upon the roller 25 to rock the arm 21 and cause it to operate the arm 20 to rock the arm 19 and the needle bar 8 on the pivot 10 to move the needles 3 forwardly and rearwardly.

Mounted to slide in suitable bearings on the machine frame is a shaft 28 which extends longitudinally of the machine or parallel with the rows of needles A and B. This shaft 28 is connected in the usual manner to the upper end of an arm 29 which is pivoted at its lower end by means of a shaft 30 to a bracket 31 on the machine frame. This arm 29 is associated with the coulier cam 32 on the coulier shaft 33 to be actuated thereby in the usual well known manner to rock the arm 32 and reciprocate the shaft 28. The shaft 33 turns in bearings on the machine frame and carries a bevel gear wheel 34 in mesh with a bevel gear wheel 35 on the cam shaft 16, whereby the coulier shaft 33 will be rotated when the cam shaft is rotated.

The thread carrier 4 is connected to and actuated by the shaft 28 in the usual manner well known in this art whereby the thread carrier is caused to travel along the row of needles and deliver the thread thereto and to the sinkers and dividers, during the knitting operation.

The sinkers 5 and dividers 6 are of usual construction, as shown in detail in Figs. 6 and 7, respectively, having upwardly extending butts 36 to 37, respectively, on their rearward ends, and having identical nose portions 38 and 39, respectively forming their forward ends, and having thread-engaging risers 40 and 41 rising from the nose por-

tions 38 and 39, respectively. The sinkers and dividers are arranged in alternate succession between the needles 3 (Fig. 8) and they are fitted to slide forwardly and rearwardly in the usual manner in suitable grooves in a bar 42, which is fixed on the frame of the machine.

The sinkers 5 are successively moved forwardly behind the thread carrier 4 as it delivers the thread thereto, and the forward movement of the sinkers is effected in the usual manner by the jacks 43 which are operated by the "slur cocks" or cams 44 carried by the cam box 45 which is slidably fitted to a bar 46 on the machine frame. The cam box 45 is secured to a bar 47 which, in turn, is secured to and forms part of a carriage 48 which slides longitudinally of the machine on a guide bar 49 fixed on the machine frame. The carriage 48 is connected to the shaft 28 in the usual manner to be reciprocated thereby to reciprocate the cam box 45 and cams 44 for the actuation of the jacks 43 and sinkers 5 in harmony with the reciprocations of the thread carrier 4 in the usual manner.

The sinkers 5 are all moved rearwardly at the same time by a catch bar 50 which extends longitudinally of the machine and which is connected to and supported at intervals by arms like the arm 51 shown in Fig. 1. Each of these arms 51 is pivoted at its forward and rearward ends to the upper ends of arms 52 and 53, respectively. The lower end of the arm 53 is fixed on a rockable shaft 54, and the lower end of the arm 52 is pivoted to an arm 55 which projects fixedly from a rockable shaft 56. The shafts 54 and 56 extend longitudinally of the machine and they are supported in suitable bearings on the frame thereof. Secured to and extending from the shaft 54 is an arm 57 carrying a roller 58 which bears against a cam 59 on the cam shaft 16; and secured to and extending from the shaft 56 is an arm 60 carrying a roller 61 which bears against a cam 62 on the shaft 16. The roller 61 is maintained in engagement with the cam 62 by the weight of the arms 51, 52 and 55 and bar 50, and the roller 58 is maintained in engagement with the cam 59 by a spring 63 connecting the free end of the arm 57 and a bracket 64 secured on the machine frame 2.

During the rotation of the cam shaft 16 the cam 59 acts upon the roller 58 and arm 57 to oscillate the shaft 54 and thereby move the arms 53 and 51 forwardly and rearwardly to effect the forward and rearward movements of the catch bar 50, and the cam acts upon the roller 62 and arms 60 to oscillate the shaft 56 and thereby raise and lower the arms 55, 52, and 51 to effect the raising and lowering of the catch bar 50.

The catch bar 50 is of usual construction, having a longitudinal groove 65 in the bottom thereof for the reception of the upward-

ly extending butts 36 and 37 on the rearward ends of the sinkers 5 and dividers 6, and it is operated and controlled by the cams 59 and 62 in the usual manner to effect the simultaneous forward movement of the dividers, and the simultaneous rearward movement of the sinkers and dividers at the proper times with relation to the movements of the needles 3 and the thread carrier 4 to effect the knitting operation.

The knock-over bits 7 are suitably supported beneath and slightly spaced from the sinkers 5 and dividers 6, one for each sinker and one for each divider. These bits 7 extend between the needles 3 in vertical alignment with the sinkers and dividers, and they serve to prevent the knit fabric 66 being produced by the machine from being lowered by and with the needles 3 when the needles are lowered or moved downwardly during the knitting operation.

The knit fabric 66 being produced by the machine as herein illustrated, is intended to represent the leg blank of a stocking having the usual welt 67 formed on the forward end thereof. The fabric extends from the needles 3 and has a rod 68 extending through the welt 67. The respective ends of the rods 68 are connected to one end of an apron 69. The other end of the apron 69 is connected to a take-up drum 70 carried by a shaft 71 which is journaled in brackets on the machine frame. The shaft 71 is provided with a wheel 72 having a cord 73 secured thereto and wound around the same. The cord 73 extends from the wheel 72 to and over an idler pulley 74 and downwardly therefrom to a suitable weight 75 which is carried by the free end thereof, as shown in Fig. 1. The gravity pull of the weight 75 turns the shaft 71 and drum 70 in the direction of the arrow, in Fig. 1, and causes the drum 70 to exert the desired pull upon the fabric 66 and to take up the fabric and the apron 69 as rapidly as the fabric is produced.

During the operation of the machine for the production of knit fabric, the thread carrier 4, one being provided for each row of needles, moves along the row of needles 3 and delivers the thread thereto above the noses 38 and 39 of the sinkers and dividers and between the needles 3 and the risers 40 and 41 of the sinkers and dividers 5 and 6, respectively. During the movement of the thread carrier 4 along the row of needles, the "slur cocks" or cams 44 operate the jacks 43 successively to advance the sinkers 5 and cause their risers 40 to engage the thread delivered by the carrier 4 and push the thread forwardly through alternate spaces between the needles 3, and cause the thread to be engaged by the needles 3 and the sinker risers 40 and thereby formed into a corrugated course, the corrugations of which extend through alternate spaces between the needles. This done,

the catch bar 50 is operated to advance all the dividers 6 simultaneously and cause their risers 41 to engage the thread previously formed into a corrugated course by the sinkers 5, and push the thread forwardly through the alternate spaces between the needles 3 which are not occupied by the sinker risers 40 while the needles 3 are moved forwardly until the thread is formed into a corrugated course, the corrugations of which extend through all the spaces between the needles 3 and are of even and uniform formation. Each needle 3 is now embraced by a corrugation of the thread, and such corrugations form a course of fresh loops to be drawn through the last previously formed loops of the fabric. The needles 3 are now moved downwardly until the fresh loops enter the openings between the bodies of the needles and the beards thereof. After the fresh loops thus enter the needle openings, the needles are moved rearwardly until the needle beards are pressed into the closed position by the forward or presser surface of the bar 42 between the sinkers and the dividers. While the beards are maintained in the closed position, the needles continue their downward movement until the free end portions of the needle beards are drawn down into the loops of the last previously formed row thereof of the finished fabric which embrace the needles. The sinkers and dividers are then simultaneously drawn rearwardly by the catch bar 50 while the needles continue their downward movement until the fresh loops within the needles 3 are drawn down between the nose portions 38 and 39 of the sinkers and dividers, respectively, and are maintained by such nose portions in even and uniform formation. The sinkers and dividers continue their rearward movement while the needles are moved forwardly and the upper ends or heads thereof are maintained substantially the same distance below the tops of the noses of the sinkers and dividers over which the fresh loops with in the needles extend. Before the sinkers and dividers complete their rearward movement, the needles are moved downwardly between them and near their forward ends, and the fresh loops extending over the sinkers and dividers move downwardly and around the free ends of the noses thereof and are discharged therefrom. The fresh loops thus discharged are then drawn by the needles down through the loops of the last previously formed row thereof which are now discharged from the needles while the knock-over bits prevent the finished fabric from moving downwardly with the needles. This done, the sinkers and dividers are moved forwardly by the catch bar 50 over the finished fabric 66 to prevent upward movement thereof by the needles, and the needles are raised to elevate their beards above the sinkers, and dividers. The catch bar 50 then moves the sinkers and

dividers rearwardly and the parts are in position for the thread carrier to again deliver the thread to the needles for the formation of a succeeding row of fresh loops to be added to the finished fabric in the next cycle of operations of the loop forming devices.

The construction and operation of the parts of the machine thus far described are well known to persons skilled in this art, and, therefore, no additional illustration or description thereof is deemed necessary herein.

When the loops of the successive rows of fresh loops are discharged from the free ends of the noses of the sinkers and dividers, in the production of knit fabric by the old mechanism hereinbefore described, they are also discharged from the holding influence of the sinkers and dividers which up to this point in the knitting operation held them in even and uniform condition; and this discharge takes place before the needles draw the fresh loops down through the loops of the last previously formed row thereof of the finished fabric. During the time between the discharge of the fresh loops from the holding influence of the sinkers and dividers and the drawing of the fresh loops through the loop of the previously formed row thereof, the thread forming the fresh loops is free to move independently through each needle. When the condition of the thread is such that it does move to some extent through some or all of the needles, due to various causes, such a variation in its moist condition and its tendency, due to inherent characteristics, to assume shapes and bends different from the shapes and bends of the loops, the result is that the length of the thread forming the respective fresh loops is increased in some of them and decreased in others, causing the production of ununiform and distorted loops in the finished fabric and the sleazy knitting which is overcome by my invention.

I shall now describe the construction and operation of the mechanism and parts thereof which I have added to and combined with the old mechanism in producing my improved machine.

Extending parallel to the row of needles is a bar 76 which is formed on or secured to the upper end of an arm 77 whose lower end is pivoted to an arm 78 which is fixed on and extends forwardly from a rockable shaft 79. The arm 77 has a slot 80 formed therein through which a guide pin 81 extends. The pin 81 is fixed to and projects from one side of a part of the bracket 9 on the needle bar 8. The free end of the pin 81 has a collar or head secured thereon outwardly of the arm 77. The arm 77 is adapted to be raised to the position shown in Fig. 3 and to be lowered to the position shown in Fig. 2 when the shaft 79 is rocked, and the arm 77 is guided in its up and down movements by the pin

81 and by and between the bracket 9 and head or collar 82.

The shaft 79 is fitted to turn in suitable bearings on the machine frame and it is provided with a forwardly extending arm 83 which is fixed thereto and has its forward end pivoted to the upper end of a link 84. The lower end of the link 84 is pivoted to an arm 85 which is pivoted on a bracket 86 on the frame of the machine. The arm 85 extends forwardly from the bracket 86 and is provided with a pin or short shaft 87 extending outwardly from one side of the forward end thereof parallel to the cam shaft 16. The pin 87 carries a roller 88 which is mounted to rotate and to slide longitudinally thereon and which rests upon a cam 89 and carries the weight of the arm 85, the link 84, the arms 83, 78 and 77, and the bar 76. During the rotation of the shaft 16 the cam 89 raises and lowers the arms 85 and 83 and link 84 and thereby rocks the shaft 79 for raising and lowering the bar 76, as previously described.

At certain times during the operation of the machine in producing stocking blanks it is desirable that the bar 76 shall not be raised and lowered by the cam 89, and, therefore, I provide the cam shaft 16 with a plain wheel 90 adjacent to the cam 89, and I provide a means for moving the roller 88 longitudinally on the pin 87 into and from a position in which it will rest upon the wheel 90 away from the influence of the cam 89.

The means for moving the roller 88 on the pin 87 to rest either upon the cam 89 or upon the wheel 90 is as follows: Fulcrumed at 91, on a projection 92 on one side of the arm 85 is a lever 93 having a pin 94 on the forward end thereof which extends into an annular groove in the hub 95 of the roller 88. The rearward end of the lever 93 extends between two collars 96 fixed on a rod 97 which extends longitudinally of the machine parallel to the cam shaft 16 and is fitted to slide longitudinally in suitable bearings on the machine frame. The rod 97 has two additional collars 98 secured thereon, and located between the collars 98 is the lower free end of an arm 99 which is fixed to and extends downwardly from the rearward end of a horizontal shaft or rod 100 which extends transversely of the machine and is fitted to turn in suitable bearings in the frame thereof. The forward end of the shaft 100 is provided with an arm or handle 101 by means of which the shaft 100 may be turned by hand to cause the arm 99 to move the rod 97 longitudinally and thereby move the lever 93 on its fulcrum 91 to move the roller 88 longitudinally on the pin 87. Thus it will be understood that by moving the handle 101 in one direction the roller 88 may be set in a position to rest upon the cam 88 to operate the bar 76, and that by moving the handle 101 in the reverse direction the roller 88 may

be set in a position to rest upon the wheel 90 to stop the operation of the bar 76. The rod 97 is provided with two collars 102 on the respective sides of a part of the machine frame to engage the same and limit the extent of movement of the handle 101 in either direction.

The bar 76 is located forwardly of the needles 3 and beneath the fabric 66 being produced by the machine. The length of the bar 76 is equal to the width of the fabric and the function of the bar is to engage the fabric and raise it with relation to the needles 3 and the sinkers and dividers from the position shown in Fig. 2 to the position shown in Fig. 3, and thereafter lower it from the position shown in Fig. 3 to the position shown in Fig. 2, in certain timed relation to the movements of the needles 3 and the sinkers 5 and dividers 6, during each cycle of operation of the loop forming devices, or each time a row of fresh loops is added to the fabric being produced.

The sinkers 5 and dividers 6 and the needles 3 are moved with relation to each other, during the knitting operation, in my improved machine, the same as they are moved with relation to each other in the well known class of knitting machines to which my invention relates.

In Figs. 9, 10, 11 and 12, I have shown the relation of the needles 3 to the free end portions of the noses 38 and 39 of the sinkers and the dividers 5 and 6 in different positions of the needles; and in Figs. 9, 10 and 11 I have indicated by arrows adjacent to the parts the direction of movement thereof when they occupy the relative positions illustrated in the several views.

The cam shaft 16 is turned one revolution during each cycle of operations of the loop forming devices, and the operation of the bar 76 by the cam 89 is so timed with relation to the movements of the needles 3 and the sinkers 5 and dividers 6 that the cam 89 will raise the bar 76 and fabric 66 when the needles 3 reach the region shown in Fig. 9 with relation to the sinkers and dividers while the needles are moving forwardly and downwardly between them; and that the cam 89 will lower the bar 76 and fabric 66 when the needles 3 reach the region shown in Fig. 11 with relation to the sinkers and dividers, while the needles are moving rearwardly below them; and that the bar 76 and fabric 66 will remain in the lowered position until the needles again reach the region shown in Fig. 9 with relation to the sinkers and dividers, during the next cycle of operations of the loop forming devices.

While the bar 76 holds the fabric 66 in the raised position shown in Fig. 3, the fabric extends upwardly as well as forwardly from the needles 3 and it is drawn upwardly on the needles and into contact with the bot-

toms of the sinkers 5 and the dividers 6; and, while the bar 76 is in the lowered position, shown in Fig. 2, the fabric 66 extends horizontally from the needles 3 substantially at right angles thereto or parallel to the plane of movement of the sinkers and the dividers for purposes presently explained.

When, during the knitting operation, the needles and the sinkers and dividers reach the relative positions shown in Fig. 9, the last row of loops, indicated at 103, of the finished fabric embracing the needles 3 are drawn upwardly on the needles and the rearward end portion of the finished fabric is in engagement with the bottoms of the sinkers and dividers, and the fresh loops, indicated at 104, formed by the thread extending through the needle openings, are embracing the noses 38 and 39 of the sinkers and dividers and are thereby being maintained in even and uniform condition.

As the needles 3 move forwardly and downwardly and the sinkers and dividers move rearwardly from the relative positions thereof, illustrated in Fig. 9, to the relative positions thereof illustrated in Figs. 10 and 12, the forward and upward pull of the finished fabric 66 draws the last row of loops 103 thereof upwardly between the sinkers 5 and dividers 6 and forwardly over the upper ends of the needles 3 while the needles draw the fresh loops 104 down through the loops 103 and before the needles move out of the spaces between the sinkers and dividers. Immediately after the fresh loops 104 escape the upper ends of the needles, the pull of the fabric 66 draws the fresh loops completely through the loops 103. The discharge of the fabric loops 103 from the needles 3, and the drawing of the fresh loops 104 through the loops 103, and the drawing of the loops 103 by the pull of the fabric 66 to final position embracing the fresh loops 104 takes place while the fresh loops 104 are held in even and uniform condition by the sinkers and dividers. Therefore, the sinkers and dividers prevent the thread forming the fresh loops 104 from moving through the needle openings while they are being added to the finished fabric 66 and thereby prevent sleazy knitting.

After the fresh loops 104 have been added to the finished fabric, as above described, the needles 3 are moved downwardly from the sinkers and dividers and rearwardly below the same; and, when the needles enter the zone with relation to the sinkers and dividers as illustrated in Fig. 11, the bar 76 lowers the fabric 66 to the horizontal position. The fabric 66 remains in horizontal position until the needles 3 and the sinkers 5 and dividers 6 again reach the relative positions shown in Fig. 9, in the next cycle of operations of the loop forming devices. Thus the fabric 66 is lowered from the position shown in Fig.

3 to the position shown in Fig. 2 to permit the sinkers 5 and dividers 6 to be moved over the fabric and into the space occupied by it when elevated as shown in Fig. 3, during the 5 operation of the loop forming devices after the parts leave the relative positions shown in Fig. 11 and until they again reach the relative positions shown in Fig. 9.

In knitting machines of the character herein illustrated it is desirable at times to move the needle bar 8 forwardly from its working position in the machine for renewing broken needles, and for other purposes the arm 20 is provided with an additional pocket 105 forwardly of the pocket 23 for the reception of the pin 22. By raising the arm 20 to free the pin 22 from the pocket 23 the arm 20 may be moved inwardly to engage the pocket 105 with the pin 22, and, when 15 this is done, the needle bar 8 will be moved forwardly on the pivotal connections of the brackets 9 with the arms 13. The pin-and-slot connection between the arm 77 and bracket 9 permits the forward movement of 20 the needle bar 8 without disturbing the proper working relation of the arm 77 and the needle bar bracket 8.

Some knitting machines of the character herein illustrated have stationary fabric supporting or knock over bits, and others have movable bits which are operated to assist the needles when they draw the successive rows of fresh loops down through the previously formed loops of the fabric. My invention 30 will operate equally well when applied to either type of machine because the assistance of the bits is not required in my invention when the needles draw the successive rows of fresh loops down through the previously 35 formed loops of the fabric.

My invention permits the presence of a greater space for the fabric between the tops of the forward end portions of the bits and the bottoms of the sinkers and dividers; and 45 my invention will produce knit fabric having even and uniform thread loops long after many of the parts of the machine have become worn to an extent which would require them to be renewed in machines not 50 provided with my improvements.

I claim as my invention:

1. In a straight knitting machine, the combination of a row of needles, actuating mechanism for the needles, take-up means 55 for knit fabric extending from the needles, supporting bits for the fabric, sinkers and dividers for cooperation with the needles for the production of knit fabric, actuating mechanism for the sinkers and dividers, said needles during the actuation 60 thereof operating to draw a course of fresh thread loops down through the last previously formed row of loops of the finished fabric embracing the needles and means 75 for raising said last previously formed row

of loops under tension into the spaces between the sinkers and dividers.

2. In a straight knitting machine, the combination of a row of needles, actuating mechanism for the needles, take-up means for knit 70 fabric extending from the needles, supporting bits for the fabric, sinkers and dividers for cooperation with the needles for the production of knit fabric, actuating mechanism for the sinkers and dividers, the sinkers and 75 dividers operating to maintain a course of fresh loops in uniform condition as such fresh loops are advanced by the needles to be thereby drawn through the last previously formed row of loops of the finished fabric 80 embracing the needles and means for raising said last previously formed row of loops under tension above the needles while said fresh loops are in operable contact with the sinkers and dividers to maintain said fresh loops in 85 uniform condition.

3. In a straight knitting machine, the combination of a row of needles, actuating mechanism for the needles, take-up means for knit 90 fabric extending from the needles, supporting bits for the fabric, sinkers and dividers for cooperation with the needles for the production of knit fabric, actuating mechanism for the sinkers and dividers, the sinkers and 95 dividers operating to maintain a course of fresh loops in uniform condition as such fresh loops are advanced by the needles to be thereby drawn through the last previously formed row of loops of the finished fabric embracing the needles and means acting on the finished 100 fabric for drawing said last previously formed row of loops under tension upwardly and forwardly over the needles while said fresh loops are in operable contact with the sinkers and dividers to maintain said fresh 105 loops in uniform condition.

4. In a straight knitting machine, the combination of a row of needles, actuating mechanism for the needles, take-up means for knit 110 fabric extending from the needles, supporting bits for the fabric, sinkers and dividers for cooperation with the needles for the production of knit fabric, actuating mechanism for the sinkers and dividers, a fabric engaging bar below the fabric forwardly of the sinkers and dividers and means for raising and lowering the bar, the bar being raised to draw the knit fabric under tension upwardly and into contact with the bottom of the sinkers and dividers while 120 the needles are moving downwardly within the spaces between the sinkers and dividers and thereafter being lowered to lower the fabric below the plane of movement of the sinkers and dividers.

5. In a straight knitting machine, the combination of a row of needles, actuating mechanism for the needles, take-up means for knit 125 fabric extending from the needles, supporting bits for the fabric, sinkers and dividers

for cooperation with the needles for the production of knit fabric, actuating mechanism for the sinkers and dividers, a fabric engaging bar below the fabric forwardly of the sinkers and dividers, a movable arm provided with a roller, a cam engaging the roller for moving the arm, actuating means for the cam, a rockable shaft, means operated by the arm for rocking the shaft, and means operated by the shaft for raising and lowering the bar, the bar being raised to draw the knit fabric under tension upwardly and into contact with the bottom of the sinkers and dividers while the needles are moving downwardly within the spaces between the sinkers and dividers and thereafter being lowered to lower the fabric below the plane of movement of the sinkers and dividers.

6. In a straight knitting machine, the combination of a row of needles, actuating mechanism for the needles, take-up means for knit fabric extending from the needles, supporting bits for the fabric, sinkers and dividers for cooperation with the needles for the production of knit fabric, actuating mechanism for the sinkers and dividers, a fabric engaging bar below the fabric forwardly of the sinkers and dividers, a cam, actuating means for the cam, means operated by the cam for raising and lowering the bar the bar being raised to draw the knit fabric under tension upwardly and into contact with the bottom of the sinkers and dividers while the needles are moving downwardly within the spaces between the sinkers and dividers and thereafter being lowered to lower the fabric below the plane of movement of the sinkers and dividers, and means operable to move the last named means into and out of operative relation to the cam.

7. In a straight knitting machine, the combination of a row of needles, actuating mechanism for the needles, take-up means for knit fabric extending from the needles, supporting bits for the fabric, sinkers and dividers for cooperation with the needles for the production of knit fabric, actuating mechanism for the sinkers and dividers, a fabric engaging bar below the fabric forwardly of the sinkers and dividers, an arm supporting the bar and extending downwardly therefrom, a rockable shaft, an arm secured to and extending from the shaft and pivoted to the first named arm, means for rocking the shaft to raise and lower the arms and the bar and guiding means for the arm which supports the bar.

8. In a straight knitting machine, the combination of a needle bar carrying a row of needles, actuating mechanism for the needle bar, take-up means for knit fabric extending from the needle, supporting bits for the fabric, sinkers and dividers for cooperation with the needles for the production of knit fabric, actuating mechanism for the sinkers and di-

viders, a fabric engaging bar below the fabric forwardly of the sinkers and dividers, an arm supporting the fabric engaging bar and extending downwardly therefrom and having a slot therein, a pin carried by the needle bar 70 and extending into said slot for guiding said arm and means pivotally connected to said arm for raising and lowering it and the fabric engaging bar.

In testimony whereof I affix my signature. 75
KURT OSWALD WAECHTLER.
